VAPORIZER

Lyle H. Critzer, Pratt, Kans.

Application November 25, 1952, Serial No. 322,528

1 Claim. (Cl. 219—19)

This invention relates to the art of disinfecting poultry houses—including brooders and hatcheries—by means of a vapor of a suitable disinfectant, and is particularly concerned with the provision of an improved vaporizer adapted for use in vaporizing a vaporizable or sublimable insecticide, such, for instance, as Lindane into the atmosphere of poultry houses, and of an improved technique of disinfecting poultry houses through vaporization of such insecticide.

An object of the invention is to provide an inexpensive, yet efficient and safe, electrically heated vaporizer adapted to operate with ordinary lighting current. Another object is the provision of a vaporizer which readily may be converted into an electric light fixture and vice versa, as required. A further inventive object is the provision of a mode of controlling the rate of vaporization of the insecticide while the temperature of the heater remains constant.

According to the present invention, the above, and other inventive objects are realized by the provision of an electric light fixture similar to a common "night light" and differing therefrom in the provision of a rotatable receptacle adapted to receive the insecticidal material to be vaporized and to support the latter in close proximity to the heat source (i. e., the bulb). A perforated cover is also provided for the receptacle to assist in regulation of the rate of vaporization and to prevent non-intended access to the receptacle.

It has been found that the heat from a 7.5 watt light bulb, applied to crystalline Lindane supported in close proximity to the lamp, is sufficient to generate, in the room containing the device, enough Lindane vapor to kill or control insects in a poultry house or room having a volume of 20,000 cubic feet. The chemical Lindane is the gamma isomer of hexachlorocyclohexane of purity better than 99 per cent. Control of the rate of vaporization can be effected by selection of a bulb giving off the amount of heat desired or/and by controlling the total effective cross-sectional area of the perforations in the cover member. Thus, in the event a less than maximum output of insecticidal vapor is desired, a suitable proportion of the perforations can be closed, as by the application thereover of an adhesive strip, whereby to reduce the volume of vapor emanating from the device; or, the normal light bulb can be replaced by a light bulb of lesser heating value.

The device of the invention is also adapted to be altered, at will, from a vaporizer to a conventional night light merely by removal of the perforated cover and removal of the vaporizable material from the receptacle which then will function as a light shield.

In the accompanying drawings which illustrate a practical embodiment of my improved vaporizer:

Fig. 1 is view in side elevation;

Fig. 2 is an end view as seen from the right in Fig. 1;

Fig. 3 is a top plan view;

Fig. 4 is a view similar to Fig. 1 but with the vaporizer chamber shown in vertical longitudinal central section;

2

Fig. 5 is a vertical transverse section taken on line 5—5 of Fig. 4, and

Fig. 6 is an end view of the receptacle element.

With reference now to the various views of the drawings 5 the vaporizer is seen to include a body member 10 having a pair of parallel spaced prongs 11 projecting from one end thereof adapted to be plugged into a conventional wall outlet (not shown) or some other socket providing a source of electric current. The opposite end of the body 10 member 10 includes a bulb socket 12 of the screw type adapted to receive a light bulb 13 which serves as a source of heat. A switch is preferably built into the body 10 to control energization of bulb 13 and is controlled by an actuating knob 14 which extends outwardly of the body. The switch (not shown) is of conventional construction and, as is well known, controls the electric circuit between the prongs 11 and bulb 13.

Surrounding bulb 13 is a cup-shaped receptacle 15 of any suitable material such as a moulded plastic from 20 which the material placed therein is vaporized. For convenience in positioning around bulb 13, the left end of the receptacle as viewed in Figs. 1 and 4 includes a yoke portion 16 which engages an annular groove 17 in the body member 10. To retain the receptacle in place on 25 the body member, the yoke portion 16 includes lugs 18 in opposed relation on the arms of the yoke, the normal distance between the lugs being slightly less than the diameter at the base of groove 17. These lugs are so located that when the receptacle is put in place, the yoke 30 is sprung slightly as the lugs pass by a diametral plane through the base of the groove, the yoke then contracting through its inherent resilient characteristic to or nearly to its original size whereby the lugs 18 serve to retain the receptacle 15 in place but yet permit rotation of 35 the same about bulb 13 for a purpose which will be explained hereinafter.

A cover member 19 is provided for receptacle 15 and may be attached thereto in any suitable manner such as for example by spring latches 20 depending from each 40 side of the cover member and which engage shouldered portions 21 on the exterior of the receptacle. Preferably the left end of cover 19 as viewed in Figs. 1 and 4 also includes a yoke portion 22 fitting into the groove 17 so that when the receptacle 15 and its cover 19 are in place, 45 the light bulb 13 is completely enclosed. Cover 19 is also provided with a plurality of small perforations 23 through which the vaporized material can escape to the surrounding atmosphere.

Although various kinds of material may be placed in 50 receptacle 15 to be vaporized the illustrated embodiment is particularly well suited for vaporization of a normally solid crystalline insecticide such as the Lindane previously mentioned. Lindane comes in granulated form and when heated passes first through the liquid phase and thence 55 into the vapor phase.

In use, the vaporizer is plugged into a wall outlet or other socket, a teaspoonful of the Lindane 24 is poured into receptacle 15 and the switch turned on to energize bulb 13. The latter being of the incandescent filamentary 60 type produces a considerable amount of heat at approximately 200° F. which serves to convert the crystalline Lindane 24 into the vapor state, the vapor passing outwardly through the perforations and into the closed space to be disinfected, e. g. a poultry house. Lindane vapor kills insects in three different ways, (1) by contact with the vapor, (2) by breathing the vapor, and (3) by eating anything that has come in contact with the vapor. The rate of vaporization can be controlled either by using a different sized bulb 13 so as to either increase or decrease 65 the heat output or by varying the total area of perforations in cover 19. This may be accomplished simply by closing off some of the perforations with adhesive tape.

The rate of vaporization is not so high as to require removal of poultry from the enclosure while the latter is being disinfected. However the material itself is quite toxic and hence the cover 19 also serves to keep the poultry from picking at or eating the granules 24.

Electrical outlets are not always installed alike. Sometimes the slots which receive prongs 11 are found side-by-side on a wall and at other times one above the other. The design of the present construction is such that regardless of the manner in which the slots are arranged, the vaporizer can be so installed that receptacle 15 containing material 24 will always rest bottom down. This desirable feature stems from the fact that receptacle 15 can be rotated about its axis on the body 10 as explained above. If the solid material to be vaporized is one which sublimes, then the attitude of repose of the receptacle is of no consequence. However, if the solid material is one which passes through a liquid phase in the process of being vaporized, which is a customary condition, then it is important always to be able to so support the receptacle 15 that the liquefied material will not spill out and thus become wasted but rather will be collected in a pool at the bottom of the receptacle, from which pool vaporization can take place. The rotatable mounting of receptacle 15 makes the latter possible regardless of the angular disposition of the slots in the wall socket into which prongs 11 are inserted.

Having now described my invention and illustrated one practical embodiment thereof, I claim:

In a vaporizer device adapted to be plugged into an electrical wall outlet, the combination comprising a body

member, a pair of parallel spaced prongs extending outwardly at one end of said body member, a socket arranged at the other end of said body member adapted to receive a light bulb, electrical connections between said prongs and socket, said electrical connections including a switch device, an imperforate cup-like receptacle adapted to receive the vaporizable material, a perforate cover for said receptacle, means securing said receptacle to said body member at the socket end thereof such that the light bulb will be disposed in said receptacle in spaced relation with respect to the latter and with its major axis substantially parallel to the major axis of said receptacle, and securing means comprising a yoke portion on said receptacle having opposed lugs engageable with a transverse peripheral groove in said body member, said cover also including a complementary yoke portion engageable with the groove in said body member, said securing means permitting relative rotation between said receptacle and body member, and means removably connecting said cover to said receptacle.
